UNITED STATES PATENT OFFICE.

PAUL A. MEEHAN, OF NEW CASTLE, PENNSYLVANIA, ASSIGNOR TO AMERICAN DRESSLER TUNNEL KILNS, INC., OF NEW YORK, N. Y., A CORPORATION OF NEW YORK.

CONTINUOUS TUNNEL-KILN.

1,355,407.

Specification of Letters Patent. Patented Oct. 12, 1920.

Application filed January 2, 1920. Serial No. 348,785.

To all whom it may concern:

Be it known that I, PAUL A. MEEHAN, citizen of the United States, and resident of New Castle, in the county of Lawrence and 5 State of Pennsylvania, have invented certain new and useful Improvements in Continuous Tunnel-Kilns, of which the following is a specification.

My present invention relates to continuous 10 kilns of the tunnel type in which the goods to be heated are moved through an elongated kiln chamber on cars which normally form a slow moving train filling the kiln, one car passing out through the exit end of the kiln 15 as fast as a fresh car is inserted at the entrance end of the kiln. Kilns of this character are well adapted for use in clay and pottery treating, metal annealing and for many other purposes, and are now in extensive 20 use in this country.

In many cases the economical use of the heat, the necessity of gradually heating up the goods treated, and for subjecting them to drying, burning or annealing temperatures 25 for considerable periods, require a kiln several hundred feet in length. The general object of my invention is to provide a kiln formed in sections disposed at an angle to one another, and coöperating apparatus, 30 which shall be relatively simple and satisfactory under the conditions of operation to which it is subjected, for moving cars through the various kiln sections, and from one section to another. I thus obtain a kiln 35 in which the over-all length of the kiln structure as a whole, is substantially less than the effective length of the kiln chamber proper.

The various features of novelty which characterize my invention are pointed out 40 with particularity in the claims annexed to and forming a part of this specification. For a better understanding of the invention, however, and the advantages possessed by it, reference should be had to the accompanying drawings and descriptive matter in 45 which I have illustrated and described a preferred embodiment of the invention.

Of the drawings:

Figure 1 is a plan with parts broken away 50 in section.

Fig. 2 is a section on the line 2—2 of Fig. 1.

Fig. 3 is a view taken similarly to Fig. 1, but on a larger scale, showing a portion only

of the apparatus and having parts broken away,

Fig. 4 is a partial section on the line 4—4 of Fig. 1 and Fig. 5 is a partial section on the line 5—5 of Fig. 1.

In the drawings I have shown a tunnel 60 kiln comprising a high temperature or hot zone A, and a heating-up zone formed of sections A', A², and A³. In the particular form of kiln illustrated, the benches B are provided at the sides of the pathway 65 through the hot zone A, for the goods carrying cars C which run on track rails D. The hot zone is heated by the combustion of fuel in, and the travel of products of combustion through, the combustion chambers E located 70 one on each bench B. As shown, gas, and air for its combustion are supplied through inlets F and G respectively, to one end of each combustion chamber, and products of combustion are withdrawn from the 75 combustion chambers at their opposite ends through ports H which are connected by a conduit H' to a draft producing device as the stack H². Each combustion chamber E is shown as formed of tile having open 80 ended ventilating channels E' through which the air or gases forming the kiln atmosphere may pass upward past and receive heat from the combustion chamber, the heated air or gases then flowing downward 85 through or along the goods on the goods carrying cars C. In the respects just noted the kiln is a typical Dressler kiln as shown, for example by patents to Conrad Dressler #1023628 and # 1170428.

In my improved kiln, a portion of the heating-up zone is out of alignment with the hot zone. As shown in the drawings, the section A' of the heating-up zone is in alignment with the hot zone, the section A² is 95 transverse to the hot zone and the section A³ is parallel to the hot zone but is laterally displaced from the latter so as to be in alignment with the return track, the track rails D³ of which extend through the section A³. To get the cars around the corner from the section A² into the section A' I employ a 100 turntable K, and to get the cars from the section A³ into the section A' I employ a turntable KA.

The turntable K is shown (see Fig. 4) as having the usual rollers K' running on a track K², and carries a gear wheel K³ in

mesh with a worm L' which may be rotated by an external hand-wheel L . The turntable K carries two sets of track rails D' and D^{10} which cross one another at right angles so that a car brought on to the turntable from the section A^2 may be moved into position to enter the section A' by a quarter turn of the turntable K . The latter is formed with notches K^4 adapted to be entered by a bolt or locking bar M to lock the turntable in either of its four operative positions. The turntable KA may be, and is shown as being, identical in construction and operation with the turntable K .

15 To pull a car from the section A^2 onto the turntable K , and center it on the latter, I employ, in the construction shown, a special car mover, comprising a bar P (see Fig. 5) which may be reciprocated in the direction of its length by means of a lever P^2 fulcrumed against the kiln wall and may be rotated by means of the handle P^2 to move its lugs P' into and out of the position in which they engage the car lugs C' as shown 20 in Fig. 5. This car moving device is disclosed and claimed in my prior Patent No. 1,326,959, granted Jan. 6, 1920. To advance the car at the head of the train normally filling the section A^3 of the kiln and 25 center it on the turntable KA , I employ a car moving device PA which may be identical with the device P already described. To push a car off the turntable K into the kiln section A' and advance the train of 30 cars normally filling that section of the kiln and the hot zone A a car length at a time, I employ a pusher O which may be of the usual type employed to push cars through tunnel kilns and as shown, comprises 35 a bar O passing through an aperture in the kiln wall in line with the zone A and section A' and reciprocated by means of an electric motor O' and suitable speed reducing gear. A similar car pusher OA is employed 40 for pushing cars off the turntable KA and into the section A^2 and for advancing a car previously located in that section a car length at a time. In the particular construction shown, the parts are so proportioned 45 that with a car centered on each of the turntables K and KA , there will be but a single car in the section A^2 . The cars are entered in the section A^3 by a car pushing device shown as comprising a belt or 50 sprocket chain T' arranged between the track rails D^3 and provided with car engaging lugs T^2 and driven by a motor T . The cars ejected from the kiln one at a time past the exit door S are received on a 55 transfer car (not shown) which may be of the usual construction and which runs on the tracks Q , and may serve to move the cars to a goods handling station or stations (not shown) before returning them to the 60 adjacent end of the return track D^3 . As

shown, a shed or housing R covers the end of the return track adjacent the transfer track and serves as a chamber in which the trucks may cool off gradually before being reinserted in the section A^3 which forms the 70 entrance end of the kiln.

In operation the cars are inserted by the chain T' , one at a time, in the entrance end of the kiln. As each car comes into proximity with the turntable KA , it is engaged 75 by the car mover PA and centered on the turntable, the latter is then given a quarter turn, after which the pusher OA is operated to push the car off the turntable KA and advance the car previously standing in the 80 kiln section A^2 into proximity to the turntable K . The car mover P is then operated to draw the adjacent car from the section A^2 on to the table K , after which the latter is given a quarter turn and the pusher O is 85 then operated to push the car off the table K into the kiln section A' and to advance the train of cars in the hot zone A and the kiln section A' a carlength. The door S being opened at the proper times to permit the 90 adjacent car to pass out of the kiln.

The particular form of tunnel kiln in which I have shown my present invention embodied is one in which the goods are taken out of the kiln at the high temperature and in which the heating-up zone is comparatively short, thus differing from the more common examples of kilns in which the heating-up zone is relatively longer and contains heat radiating conduits and in 95 which the kiln chamber is extended beyond the exit end of the high temperature zone A to form a cooling zone ordinarily containing conduits for a cooling fluid. I mention this difference between the particular form of kiln illustrated and more common types of tunnel kilns, to emphasize the fact that such a difference is not a characteristic of my present invention, which is equally applicable to many different forms of tunnel kilns. 100

With the simple and practical construction illustrated it is possible to provide a kiln chamber of the proper length to insure a given capacity with a gradual heating up 115 of the goods and the exposure of the latter to heating or drying temperatures for suitably prolonged periods with an over-all kiln length substantially less than the effective length of the kiln chamber. The practical importance of this will be apparent when it is understood that for efficient and satisfactory service it is frequently necessary to make the effective length of the kiln chamber substantially greater than the length of 120 an ordinary city block, and heretofore this fact has prevented the installation of continuous tunnel kilns in places where they would otherwise have been installed. The arrangement of the kiln in two parallel sec- 125 130

tions connected by a transfer section as in the particular form of my invention illustrated possesses the satisfactory advantage that one section of the kiln may be in alinement with the return track. The mechanism shown for transferring cars from one kiln section to another out of alinement with the first section are simple, compact and well adapted for continuous use under 10 the temperature conditions to which they may be subjected. A special advantage of the construction which may be of much practical importance in some cases arises from the fact that the same end of each 15 car remains the front end of the car in the various sections of the kiln.

While in accordance with the provisions of the statutes I have illustrated and described the best form of embodiment in my 20 invention now known to me it will be apparent to those skilled in the art that changes may be made in the form of apparatus disclosed without departing from the spirit of my invention as set forth in the 25 appended claims and that in some cases certain features of my invention may be used to advantage without a corresponding use of other features.

Having now described my invention, 30 what I claim as new and desire to secure by Letters Patent, is:

1. In a continuous kiln of the tunnel type, an elongated kiln chamber comprising two sections meeting at an angle and a turntable 35 within the kiln chamber at the junction of said sections for receiving a goods carrying car approaching the table from one section and rotating it into alinement with the other section.

40 2. In a continuous kiln of the tunnel type an elongated kiln chamber comprising two sections meeting at a right angle and each provided with a track for goods carrying

cars and a turntable within the kiln chamber at the junction of said sections provided 45 with two sets of tracks meeting at a right angle and adapted to register one with the track in one of said sections and the other with the track in the other section in either of four angular adjustments of the turntable.

3. In a continuous kiln of the tunnel type an elongated kiln chamber comprising two sections meeting at an angle, a turntable within the kiln chamber at the junction of 55 said sections for successively receiving goods carrying cars approaching the table from one section and rotating it into alinement with the other section, a car advancing device for engaging each of the cars successively approaching the turntable and moving it on to, and centering it on the turntable, and a car pushing device for engaging each of the cars successively centered on the turntable and pushing it into, and thereby advancing 60 the train of cars in, said other section.

4. In a continuous kiln of the tunnel type, an elongated kiln comprising two sections arranged side by side and a transfer section connected at one end to one, and at the other 70 end to the other of the first mentioned pair of sections and a turntable within the kiln chamber at each junction of the transfer section with the other two sections, tracks for goods carrying cars in the three kiln 75 chamber sections and tracks on the turntable, each turntable track being adapted to register with the track in one of the adjacent kiln chamber sections in one angular adjustment of the turntable and with the 80 track in the other adjacent section in another angular adjustment.

Signed at New Castle, in the county of Lawrence and State of Penna., this 27th day of December, A. D. 1919.

PAUL A. MEEHAN.
